UNITED STATES PATENT OFFICE

THADE CHRISTIANSEN, OF BALTIMORE, MARYLAND.

IMPROVEMENT IN BALLOT-BOXES.

Specification forming part of Letters Patent No. **214,622**, dated April 22, 1879; application filed February 14, 1879.

To all whom it may concern:

Be it known that I, THADE CHRISTIANSEN, of Baltimore city, State of Maryland, have invented certain new and useful Improvements in Ballot-Boxes; and I hereby declare the same to be fully, clearly, and exactly described as follows, reference being had to the accompanying drawings, in which—

Figure 1 is a plan view of the box, the lid being removed; and Fig. 2 is a central vertical sectional view of the same.

My invention has for its object to furnish a ballot-box which it is practically impossible to "stuff" by reason of the cancellation of all properly-voted tickets, the announcement of their entrance into the ballot-box by a stroke of a bell, and by the coincident impression of a mark upon a fillet of paper furnished by the Federal or municipal authorities as the case may be.

In the accompanying drawings, A is the box proper, having a hinged lid, adapted to be sealed by a signature-lock or in any other desired way. A pair of rollers, *a a*, are arranged to revolve in contact with each other, being geared together by means of cog-wheels *e e*. These rollers are covered with rubber or equivalent elastic material, *a''*, and one of them is provided with a series of teeth or points, *a'*, which may be arranged to form definite characters. The roller having the teeth need not necessarily be covered with rubber; but, by preference, it is. An ordinary inking-roller, *g*, is mounted in the box in such manner as to ink the teeth *a'*.

The shaft of one of the rollers carries an arm, *c'*, which, as the roller is revolved, engages with the clapper *c* of a bell, C, and a crank, E, having a suitable handle, is secured to one of the roller-shafts. B is a partition near one side of the box A, forming a compartment, within which is mounted the wheel *b*, which carries the fillet of paper *b'*. This latter is led between the rollers *d' d'*, which are similar in size and construction to the rollers *a a*, one of them being provided with teeth *b''*, as shown in Fig. 1.

D is a rod, which passes through the box from side to side, and is adapted to slide longi-

tudinally to a distance measured by that between the exterior knob and a pin, *f*. When withdrawn to the position shown in Fig. 1, a lock, G, is secured through the rod on the outside of the box and contiguous thereto. In this position the rod extends, as shown, sufficiently far to prevent the rotation of the rollers by interfering with the crank. This rotation is further prevented by the peculiar construction of the rod within the box, a slot, *d*, being formed in the rod, which admits of the passage of the arm *c'* when the rod is retracted, but defeats it when it is drawn out, as shown.

In operation, the fillet of paper being led between the rollers *d' d'* and the rod being retracted, the ballots are inserted through the funnel F. As the crank is turned the rollers *a a* seize the ballot, which, in passing between them, receives the impression of the teeth *a'* and falls into the box. Coincidently the bell rings and a mark is made on the fillet of paper. When the poll is closed the rod is drawn out and locked in the position shown in Fig. 1, preventing the insertion of any more ballots.

As the number of tickets properly voted must necessarily agree with the number of marks on the fillet *b'*, a complete check is furnished against "stuffing" the box with single tickets, while the peculiar arrangement of the rollers *a a* serves to infallibly prevent the undetected insertion of "padding tickets." Every ballot which passes between these rollers receives an impression from the teeth *a'*, and every properly-voted ballot is inked at the same time. The enveloping ticket, of course, prevents the inking of its contents, which, when the box is opened, must stand confessed.

The rubber covering of the rollers serves to firmly grasp the ticket while admitting of its being indented by the teeth *a'*.

The term "padding ticket," above used, designates the form of ballot alleged to be in somewhat general use in the larger cities. It consists of an enveloping ticket of the proper size and shape, folded together, and inclosing a number of other tickets. My invention is designed to prevent their use or to detect and expose it.

What I claim is—

1. In combination with the rollers *a a* and arm *c'*, the slotted bar *D*, substantially as described.
2. In combination with the rollers *a a*, *d' d'*, and arm *c'*, the bell *C*, and fillet *b'*, substantially as described.
3. The box *A*, containing the rollers *a a*, adapted to receive and mark the ticket, as set forth, in combination with the rollers *d' d'*, con-

tained within a compartment of the box having the fillet-wheel *b*, as described.

4. In a ballot-box having a pair of rollers for receiving the ballots, mechanism operated from without the box for locking the rollers when desired, substantially as set forth.

THADE CHRISTIANSEN.
